(57) **CLAIM**

I claim the ornamental design for a headgear, as shown and described.

DESCRIPTION

FIG. 1 is a front perspective view of a headgear showing my new design;

FIG. 2 is a front view of the headgear of FIG. 1;

FIG. 3 is a back view of the headgear of FIG. 1;

FIG. 4 is a top view of the headgear of FIG. 1;

FIG. 5 is a bottom view of the headgear of FIG. 1;

FIG. 6 is a left side view of the headgear of FIG. 1, the right side view being a mirror image;

FIG. 7 is a front perspective view of a second embodiment thereof;

FIG. 8 is a front view of the headgear of FIG. 7;

FIG. 9 is a back view of the headgear of FIG. 7;

FIG. 10 is a top view of the headgear of FIG. 7;

FIG. 11 is a bottom view of the headgear of FIG. 7;

FIG. 12 is a left side view of the headgear of FIG. 7, the right side view being a mirror image;

FIG. 13 is a front perspective view of a third embodiment thereof;

FIG. 14 is a front view of the headgear of FIG. 13;

FIG. 15 is a back view of the headgear of FIG. 13;

FIG. 16 is a top view of the headgear of FIG. 13;

FIG. 17 is a bottom view of the headgear of FIG. 13; and, FIG. 18 is a left side view of the headgear of FIG. 13, the right side view being a mirror image.

The broken lines are for illustrative purposes only and do not constitute any part of the claimed design.
